EXTENSIBLE SKI STICK

Gunnar Tveten, Aker, near Oslo, Norway

Application September 10, 1946, Serial No. 695,975
In Norway December 28, 1944

9 Claims. (Cl. 280—11.37)

1

The present invention relates to extensible ski poles of the type that are composed of two or more relatively displaceable and lockable members.

Such poles usually comprise two telescopic tubes, for instance, tubes of steel or aluminum, and the outer or upper tube forms the handle and surrounds the tube below.

The novel features which I consider as characteristic for my invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a view, partly in section, of a portion of an extensible ski pole illustrating the pole in its extreme collapsed condition;

Fig. 2 illustrates in a similar manner the ski pole when extended to about its maximum length;

Fig. 3 shows on an enlarged scale, an axial section through the top part of the ski pole shown in Fig. 1;

Fig. 4 is a section on lines IV—IV of Fig. 3;

Fig. 5 is a section on lines V—V of Fig. 3;

Fig. 6 is a longitudinal section showing in separate relationship the collar provided at the top of the inner tube and after removal of the spindle emphasized in the device;

Fig. 7 is an end view of the collar; and

Fig. 8 illustrates, on a somewhat larger scale, a section through the top end of the inner tube and collar with the spindle extending from the collar.

As appears from the drawings, the ski pole comprises a generally hexagonal tube 1, that is movably fitted over the tube 2. The latter may extend to the bottom end of the ski pole or it may be secured to the end of a tube of still smaller diameter, which then may form the bottom part of the ski pole. The lowermost portion 1' of tube 1 is cylindrical and closely fits over tube 2.

Secured in the top end of tube 1 by means of screws 4 is a hexagonal metallic plug 3 having an axial bore, in which a spindle 7 is freely rotatable. The top end of said spindle projects somewhat beyond tube 1 and plug 3 and is provided with a knurled circular or polygonal knob 6, which serves as a finger piece for rotating the spindle relatively to the outer tube. Suitably the knob is at its underside provided with a recess forming bearing for a flange 3' of the plug 3. Just below the plug 3 the spindle 7 is provided with a stop abut-

ment for the inner end of the plug in order to prevent axial displacement of the spindle.

The abutment may consist of a nut 8 screwed onto the spindle and locked by means of a locking nut 9, or it may be connected to the spindle by welding or the like.

Below plug 3 the spindle 7 is provided with screw threads or transverse serrations 23 which are entirely or in part cut away at two opposite sides of the spindle. For this purpose the spindle is flattened slightly so that flat portions 7' intervene between the threaded portions. The spindle thus attains a cross sectional shape as shown in Figure 8.

15 The rod 7 is adapted to be received in an axial opening of a collar or sleeve 10 secured in the top end of the inner tube 2. The collar may be force-fitted into the wall of tube 2, or may be secured thereto in any other suitable manner. A hexagonal portion 10' of the collar extends beyond the end of tube 2, and slidably fits into hexagonal tube 1. Thus tubes 1 and 2 are locked against relative rotation.

10 The axial bore of the collar or sleeve 10 and 20 the portion 10' thereof are provided with internal screw threads or transverse serrations 12 which cooperate with the external threads or serrations 23 of the spindle 7. The screw threads of the collar are likewise entirely or partially cut away at two opposite sides, as indicated at 11 in Fig.

25 8, so that screw threads remain only at opposite sides of the bore, which latter thus obtains an oblong cross sectional shape. The central angle of each screw thread is 90°, or preferably a little less, both on spindle 7 and collar 10, 10'.

When the spindle 7, by means of the knob 6 is rotated to a position where the screw threads of the spindle engage the screw threads of the collar 10, 10', the outer tube will be locked to the inner tube 2. If the ski pole is to be extended or shortened, the knob 6 and thus also the spindle 7 is rotated about 90° to that angular position where the threads of the spindle are entirely out of engagement with the threads of the collar 10, 10'.

40 The screw threads of the spindle then will be located in the spaces 11, Figure 8, of the collar. Now spindle 7 and thus also outer tube 1 may be displaced longitudinally until the ski pole attains the desired length, whereafter locking is effected by turning the spindle 7, by means of knob 6, by 90°, into a position where the screw threads of spindle and collar engage.

45 In order to prevent that the spindle 7 be entirely pulled out of collar 10, 10', the inner end 50 portion of the spindle may have screw threads

about its entire periphery. On assembling the pole, such end portion must then be screwed entirely through the collar. Preferably, however, the inner end of the spindle is provided with a suitable stop abutment, for instance in the shape of nuts 13.

In order to easily ascertain the two angular positions of the spindle in locked and unlocked condition, a ball or the like 15 is provided in each of say, two opposite holes. The balls are actuated by spring 14 and are adapted to rest alternatively in one or the other wall of recesses 16, disposed at positions displaced 90° relatively in each other on the underside of knob 6. When the spindle is in locked or in unlocked position, the balls are pressed into the recesses 16. When the spindle is rotated from one position to another, a certain force must be exerted in order to bring the balls out of the recesses and the correct angular position of the spindle may thus easily be ascertained.

When the spindle 7 is rotated from locked to unlocked position, the screw threads on the spindle must be located just in front of the cut away thread portions of collar 10. In order to ensure that the spindle is in such proper position, the collar 10 is provided with, for instance, two radial holes 17, in which are seated balls 18. The balls are urged toward the spindle by means of springs 19. The holes are diametrically opposed and are spaced axially by a distance corresponding to one or several thread pitches. Further, the holes have such angular positions, that the balls 18 are pressed against the threads of spindle 7 when the latter is in unlocked position. When the spindle is moved the balls will ride over the threads and thus cause a vibration which is audible and tangible. When the spindle is stopped in a certain position for locking, it is easy to feel whether the balls are in between two threads.

The collar 10, 10' is provided at its ends with short helical springs 20 and 21 which are secured in grooves 22. When the spindle 7 is moved to one of its end positions, one or the other spring will abut against the corresponding abutment nut 9 or 13, whereby a certain resiliency is obtained. The balls 18 will thus tend to place themselves into the thread grooves even at the end positions of the spindle. Moreover, said springs will prevent undue stress upon the device.

The arrangement described may also be used for a ski pole consisting of wood, since the inner tube need not be a thin-walled metallic tube, but may be replaced by a common wooden rod having a narrow axial bore in its top portion for reception of the spindle and a wider bore for reception of the collar.

It will be understood that each of the elements described above, or two or more together, may also find a useful application in other types of ski poles, differing from the type described above.

While I have illustrated and described the invention as embodied in ski poles having two telescoping tubes, I do not intend to be limited to the details shown, since various modifications and structural changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention and, there-

fore, such adaptations should and are intended to be comprehended within the meaning and range of equivalence of the following claims.

What I claim as new and desire to secure by Letters Patent is:

1. An extensible ski pole comprising in combination a plurality of telescoping tubes; a spindle rotatably mounted in one of said tubes; a collar encircling said spindle and being operatively connected to another of said tubes; cooperating transversal serrations provided at spaced longitudinal portions of said spindle and collar; and, intervening said serrated portions, flattened portions extending lengthwise of said spindle and collar whereby a relative turning of the spindle and the collar will bring alternatively said serrations into engagement and said flat portions into register and will thus effect locking or unlocking of said tubes against relative axial movement.

15 2. An extensible ski pole comprising in combination a pair of telescoping tubes; a plug mounted in the top end of the outer tube and being provided with an axial bore; a spindle extending through said bore and rotatable therein; means for locking said spindle against axial movement relative to said plug; handle means disposed at the outer end of the spindle for rotating the same; a collar encircling said spindle and being operatively connected to the inner tube; means for preventing relative rotation of said tubes; cooperative transversal serrations provided at spaced longitudinal portions of said spindle and collar; and, intervening said serrated portions, flattened portions extending lengthwise of said spindle and collar whereby a relative turning of the spindle and the collar will bring alternatively said serrations into engagement and said flat portions into register and will thus effect locking or unlocking of said tubes against relative axial movement.

25 3. An extensible ski pole constructed in accordance with claim 2, wherein the collar is provided with a reduced downward extension and wherein

30 the said extension is force-fitted into the inner of said tubes.

35 4. An extensible ski pole comprising in combination a pair of telescoping tubes; a spindle rotatably mounted in the outer of said tubes; a collar encircling said spindle and being connected to the top end of the inner of said tubes; means for preventing relative rotation of said tubes;

40 5. An extensible ski pole comprising in combination a pair of telescoping tubes; a spindle rotatably mounted in the outer of said tubes; a collar encircling said spindle and being connected to the top end of the inner of said tubes; means for preventing relative rotation of said tubes;

45 6. An extensible ski pole comprising in combination a pair of telescoping tubes; a spindle rotatably mounted in the outer of said tubes; a collar encircling said spindle and being connected to the top end of the inner of said tubes; means for preventing relative rotation of said tubes;

50 7. An extensible ski pole comprising in combination a generally polygonal outer rod; an inner rod; a spindle rotatably mounted in said outer rod; a polygonal collar encircling said spindle and being slidably fitted in said outer rod and being connected to said inner rod; cooperating transversal serrations provided at spaced longitudinal portions of said spindle and collar; and, intervening said serrated portions, flattened portions extending lengthwise of said spindle and collar whereby a relative turning of the spindle and the collar will bring alternatively said serrations into engagement and said flat portions into register and will thus effect locking or unlocking of said tubes against relative axial movement.

55 8. An extensible ski pole comprising in combination a generally polygonal outer rod; an inner rod; a spindle rotatably mounted in said outer rod; a polygonal collar encircling said spindle and being slidably fitted in said outer rod and being connected to said inner rod; cooperating transversal serrations provided at spaced longitudinal portions of said spindle and collar; and, intervening said serrated portions, flattened portions extending lengthwise of said spindle and collar whereby a relative turning of the spindle and the collar will bring alternatively said serrations into engagement and said flat portions into register and will thus effect locking or unlocking of said tubes against relative axial movement.

60 9. An extensible ski pole comprising in combination a generally polygonal outer rod; an inner rod; a spindle rotatably mounted in said outer rod; a polygonal collar encircling said spindle and being slidably fitted in said outer rod and being connected to said inner rod; cooperating transversal serrations provided at spaced longitudinal portions of said spindle and collar; and, intervening said serrated portions, flattened portions extending lengthwise of said spindle and collar whereby a relative turning of the spindle and the collar will bring alternatively said serrations into engagement and said flat portions into register and will thus effect locking or unlocking of said tubes against relative axial movement.

65 10. An extensible ski pole comprising in combination a generally polygonal outer rod; an inner rod; a spindle rotatably mounted in said outer rod; a polygonal collar encircling said spindle and being slidably fitted in said outer rod and being connected to said inner rod; cooperating transversal serrations provided at spaced longitudinal portions of said spindle and collar; and, intervening said serrated portions, flattened portions extending lengthwise of said spindle and collar whereby a relative turning of the spindle and the collar will bring alternatively said serrations into engagement and said flat portions into register and will thus effect locking or unlocking of said tubes against relative axial movement.

11. An extensible ski pole comprising in combination a generally polygonal outer rod; an inner rod; a spindle rotatably mounted in said outer rod; a polygonal collar encircling said spindle and being slidably fitted in said outer rod and being connected to said inner rod; cooperating transversal serrations provided at spaced longitudinal portions of said spindle and collar; and, intervening said serrated portions, flattened portions extending lengthwise of said spindle and collar whereby a relative turning of the spindle and the collar will bring alternatively said serrations into engagement and said flat portions into register and will thus effect locking or unlocking of said tubes against relative axial movement.

12. An extensible ski pole comprising in combination a generally polygonal outer rod; an inner rod; a spindle rotatably mounted in said outer rod; a polygonal collar encircling said spindle and being slidably fitted in said outer rod and being connected to said inner rod; cooperating transversal serrations provided at spaced longitudinal portions of said spindle and collar; and, intervening said serrated portions, flattened portions extending lengthwise of said spindle and collar whereby a relative turning of the spindle and the collar will bring alternatively said serrations into engagement and said flat portions into register and will thus effect locking or unlocking of said tubes against relative axial movement.

13. An extensible ski pole comprising in combination a generally polygonal outer rod; an inner rod; a spindle rotatably mounted in said outer rod; a polygonal collar encircling said spindle and being slidably fitted in said outer rod and being connected to said inner rod; cooperating transversal serrations provided at spaced longitudinal portions of said spindle and collar; and, intervening said serrated portions, flattened portions extending lengthwise of said spindle and collar whereby a relative turning of the spindle and the collar will bring alternatively said serrations into engagement and said flat portions into register and will thus effect locking or unlocking of said tubes against relative axial movement.

14. An extensible ski pole comprising in combination a generally polygonal outer rod; an inner rod; a spindle rotatably mounted in said outer rod; a polygonal collar encircling said spindle and being slidably fitted in said outer rod and being connected to said inner rod; cooperating transversal serrations provided at spaced longitudinal portions of said spindle and collar; and, intervening said serrated portions, flattened portions extending lengthwise of said spindle and collar whereby a relative turning of the spindle and the collar will bring alternatively said serrations into engagement and said flat portions into register and will thus effect locking or unlocking of said tubes against relative axial movement.

15. An extensible ski pole comprising in combination a generally polygonal outer rod; an inner rod; a spindle rotatably mounted in said outer rod; a polygonal collar encircling said spindle and being slidably fitted in said outer rod and being connected to said inner rod; cooperating transversal serrations provided at spaced longitudinal portions of said spindle and collar; and, intervening said serrated portions, flattened portions extending lengthwise of said spindle and collar whereby a relative turning of the spindle and the collar will bring alternatively said serrations into engagement and said flat portions into register and will thus effect locking or unlocking of said tubes against relative axial movement.

register and will thus effect locking or unlocking of said rods against relative axial movement.

6. An extensible ski pole comprising in combination a plurality of telescoping tubes; a spindle rotatably mounted in one of said tubes; a collar encircling said spindle and being operatively connected to another of said tubes; end abutments provided on said spindle for limiting axial movement of the same with relation to said collar; resilient means disposed at the ends of said collar for coaction with said abutments in the two axial end positions of said spindle; cooperating transversal serrations provided at spaced longitudinal portions of said spindle and collar; and, intervening said serrated portions, flattened portions extending lengthwise of said spindle and collar whereby a relative turning of the spindle and the collar will bring alternatively said serrations into engagement and said flat portions into register and will thus effect locking or unlocking of said tubes against relative axial movement.

7. An extensible ski pole comprising in combination a pair of telescoping tubes; a plug mounted in the top end of the outer tube and being provided with an axial bore; a spindle extending through said bore and rotatable therein; means for locking said spindle against axial movement relative to said plug; handle means disposed at the outer end of the spindle for rotating the same; a collar encircling said spindle and being operatively connected to the inner tube; means for preventing relative rotation of said tubes; a handle piece, the said handle piece resting with its underside on said plug; a plurality of spaced recesses and spring actuated elements provided on said plug and said handle piece for releasably holding said handle piece and spindle in selected angular positions; cooperative transversal serrations provided at spaced longitudinal portions of said spindle and collar; and, intervening said serrated portions, flattened portions extending lengthwise of said spindle and collar whereby a relative turning of the spindle and the collar will bring alternatively said serrations into engagement and said flat portions into register and will thus effect locking or unlocking of said tubes against relative axial movement.

8. An extensible ski pole comprising in combination a plurality of telescoping tubes; a spindle

rotatably mounted in one of said tubes; a collar encircling said spindle and being operatively connected to another of said tubes; cooperating transversal serrations provided at spaced longitudinal portions of said spindle and collar; a plurality of axial bores provided in said collar; a plurality of spring actuated elements disposed in said bores for yieldingly bearing against the serrated portions of said spindle; and, intervening said serrated portions, flattened portions extending lengthwise of said spindle and collar whereby a relative turning of the spindle and the collar will bring alternatively said serrations into engagement and said flat portions into register and will thus effect locking or unlocking of said tubes against relative axial movement.

9. An extensible ski pole comprising in combination a plurality of telescoping tubes; a spindle rotatably mounted in one of said tubes; a collar encircling said spindle and being operatively connected to another of said tubes; end abutments provided on said spindle for limiting axial movement of the same with relation to said collar; resilient means disposed at the ends of said collar for coaction with said abutments in the two axial end positions of said spindle; cooperating transversal serrations provided at spaced longitudinal portions of said spindle and collar; and, intervening said serrated portions, flattened portions extending lengthwise of said spindle and collar whereby a relative turning of the spindle and the collar will bring alternatively said serrations into engagement and said flat portions into register and will thus effect locking or unlocking of said tubes against relative axial movement.
